UNITED STATES PATENT OFFICE.

JOSEPH M. BENNINGHOFF, OF BRYAN, OHIO.

SIGNAL.

Application filed June 5, 1922. Serial No. 565,918.

To all whom it may concern:

Be it known that I, JOSEPH M. BENNINGHOFF, a citizen of the United States, residing at Bryan, county of Williams, State of Ohio, have invented certain new and useful Improvements in Signals, of which the following is a specification.

This invention relates to improvements in signals.

10 The main objects of this invention are:

First, to provide an automatic signal for street traffic which is adapted to alternately display signals, such as Stop and Go, the intervals between the displaying of signals 15 being uniformly timed.

Second, to provide an improved signal mechanism having these advantages which is simple and economical in structure and not likely to get out of repair.

20 Further objects, and objects relating to structural details, will definitely appear from the detailed description to follow.

I accomplish the objects of my invention by the devices and means described in the 25 following specification. The invention is clearly defined and pointed out in the claims.

A structure, which is a preferred embodiment of my invention is clearly illustrated in the accompanying drawing, forming a 30 part of this specification, in which:

Fig. I is a perspective view of my improved signal.

Fig. II is a detail view partially in vertical section on a line corresponding to line 35 2-2 of Figs. III and IV.

Fig. III is a vertical section on a line corresponding to line 3-3 of Fig. IV, the upper end of the shaft and standard being broken away.

0 Fig. IV is a horizontal section on a line corresponding to the broken line 4-4 of Fig. III.

Fig. V is a detail view partially in vertical section showing the driving wheel in engagement with the star wheel, the parts being about to complete a shifting operation.

Fig. VI is a diagrammatic view of the electric wiring.

Fig. VII is a detail vertical section illustrating details of the electrical connections.

In the drawing similar reference characters refer to similar parts throughout the several views, and the sectional views are taken looking in the direction of the little arrows at the ends of the section lines.

55 Referring to the drawing, I provide a

housing 1 which constitutes a base, the housing being provided with a door 2 having a lock 3, so that only authorized persons have access to the mechanism within the 60 housing.

Within the housing is a base 4 carrying a tubular standard 5 on the upper end of which is a lamp 6. The tubular shaft 7 is rotatably mounted upon the standard 5 and 65 carries the lantern or lamp housing 8 and the signal member 9 having the words Stop and Go thereon. The lamp housing is rectangular in cross section and is provided with panes 10 which may be colored as desired, 70 as, for instance, a red pane for the Stop side and a white pane for the Go side.

The circuit wires 11 for the lamp are arranged longitudinally of the standard. At the base of the standard is a ratchet-like 75 positioning cam member 12 having four ratchet-like cams. The shaft 7 is provided with a coacting positioning member 13 riding on the cam member 12 so that as the shaft 7 is rotated the cams of the member 80 13 ride upon the member 14 and drop from their high points, thus serving to position the signals.

A coil spring 15 is arranged on the shaft within the housing, the upper end of the 85 spring being supported by the thrust collar 16 adjustably mounted on the shaft by means of the set screws 17. This spring prevents overthrow of the shaft, although the weight of the shaft and the parts carried 90 thereby act to the same end. The shaft is driven with a step by step movement, the shaft being provided with a star wheel 18 which is engaged by the tappet 19 on the driving wheel 20 as the driving wheel revolves, thereby securing a step by step rotation of the shaft. The tappet 19 is preferably a roller to minimize friction. The driving wheel 20 is connected to the motor 21 by means of a train of gears, designated 100 generally by the numeral 22, the train of gears being such that the shifting of the signal is properly timed.

A switch 23 is provided within the housing to control the motor. A switch 24 controls the lamp. Of course it is not necessary that the lamp shall be lighted during the daylight hours. The wiring is shown diagrammatically in Fig. VI.

The signal is connected to the source of 110 electrical supply through the wire indicated at 25. The signal member 9 constitutes a

housing for the illuminating lamps 26. These lamps are connected by the cables 27 to the contact rings 28 set in the insulating plate 29. Contact rings 30 carried by the plate 31 mounted on the shaft 5 are provided to coat with the rings 28. The rings 30 are connected by the branch cables 32 to the main cable 11. With the parts thus arranged the swinging of the signal member 9 does not break the electrical connections for its lamps.

I preferably provide a street sign 33 provided with a lamp 34, shown in the diagrammatic Fig. VI, the street sign being controlled by the switch 35.

My improved signal is entirely automatic in its operation, the parts being designed with a view of durability and positiveness of operation.

I have not attempted to illustrate or describe certain adaptations or modifications which I contemplate, as I believe the disclosure made will enable those skilled in the art to which my invention relates to embody or adapt the same as may be desired.

Having thus described my invention, what I claim as new and desire to secure by Letters Patent, is:

1. In a device of the class described, the combination of a housing, constituting a base, a standard projecting upwardly from said housing, a tubular shaft rotatably mounted on said standard, an actuated member mounted on said shaft, a ratchet-like positioning cam mounted within said housing at the base of said standard, a ratchet-like positioning member on the lower end of said shaft riding upon said positioning cam, a star wheel on said shaft having teeth corresponding with the cams of said positioning member, a driving wheel provided with a tappet adapted to engage with a tooth of said star wheel on

each revolution whereby the shaft is rotated with a step by step movement, a motor within said housing, and a train of gears connecting said motor to said driving wheel.

2. In a device of the class described, the combination of a housing constituting a base, a standard projecting upwardly from said housing, a tubular shaft rotatably mounted on said standard, an actuated member mounted on said shaft, a ratchet-like positioning cam mounted within said housing at the base of said standard, a ratchet-like positioning member on the lower end of said shaft riding upon said positioning cam, a star wheel on said shaft having teeth corresponding with the cams of said positioning member, and driving means including a driving wheel provided with a tappet adapted to engage with a tooth of said star wheel on each revolution whereby the shaft is rotated with a step by step movement.

3. In a device of the class described, the combination of a housing, a base, a standard projecting upwardly from said housing, a tubular shaft rotatably mounted on said standard, an actuated member mounted on said shaft, a ratchet-like positioning cam mounted within said housing at the base of said standard, a ratchet-like positioning member on the lower end of said shaft riding upon said positioning cam, a star wheel on said shaft having teeth corresponding with the cams of said positioning member, a spring mounted on said shaft within said housing, said shaft being provided with a thrust collar for said spring, and driving means including a driving wheel provided with a tappet adapted to engage with a tooth of said star wheel on each revolution whereby the shaft 1 is rotated with a step by step movement.

In witness whereof I have hereunto set my hand and seal.
JOSEPH M. BENNINGHOFF. [L.S.]
